SPECIFICATION forming part of Design No: 33,001, dated July 24, 1900.

Application filed June 21, 1900. Serial No. 21,112. Term of patent 7 years.

To all whom it may concern:

Be it known that I, EDWARD BEACH GALLAHER, a citizen of the United States, and a resident of the borough of Manhattan, in the city and State of New York, have invented and produced a new and original Design for the Side Frame of a Vehicle-Seat, of which the following is a specification, reference being had to the accompanying drawings, forming part thereof.

Figure 1 is an exterior side view of a side frame of my design; Fig. 2, an interior side view of the said frame; Fig. 3, an upper edge view of the same; Fig. 4, a horizontal section in the line 4 4 of Fig. 1; Fig. 5, a vertical section in the line 5 5 of Fig. 1; Fig. 6, a vertical section in the line 6 6 of Fig. 1.

As shown in the drawings, the leading or material feature of my design is its profile, consisting of an upright member A, a lower horizontal member B, projecting forward from the lower part of the upright member A, and an upper horizontal member C, projecting rearward from the upper part of the up-

right member A, the upright member A 25 having its edges parallel, the upper and lower members B C being taper, the lower member B having its end turned upward, the union between A and B being formed by inner and outer curves a b, and the union between A and C being formed by an outer angle c and an inner curve d. The member A has in it upright oblong openings e e, and the horizontal members have openings f g. On the outer face (shown in Fig. 1) is a marginal bead 35 h and on the inner face a marginal bead i.

What I claim, and desire to secure by Letters Patent, is—

The design for the side frame of a vehicle-seat, herein shown and described. 40

In testimony that I claim the foregoing as my invention I have signed my name, in presence of two witnesses, this 20th day of June, 1900.

EDWARD BEACH GALLAHER.
